UNITED STATES PATENT OFFICE.

CHRISTEN CHRISTENSEN, OF COPENHAGEN, DENMARK.

APPARATUS FOR COOLING MOLTEN OR EMULSION-LIKE SUBSTANCES ON A COOLING-SURFACE.

1,130,670.

Specification of Letters Patent.

Patented Mar. 2, 1915.

Application filed February 8, 1913. Serial No. 747,176.

To all whom it may concern:

Be it known that I, CHRISTEN CHRISTENSEN, subject of the King of Denmark, residing at Øster Farimagsgade 73, Copenhagen, Denmark, have invented new and useful Improvements in Apparatuses for Cooling Molten or Emulsion-Like Substances on a Cooling-Surface, of which the following is a specification.

- 10 The present invention refers to an apparatus for spreading and smoothing molten or emulsion-like substances, such as cocoa-fat and margarin respectively as a coating of desired thickness on a cooling surface.
- 15 Several types of such apparatus are known and the essential feature of the new apparatus is the provision of two mutually independent members, adjustable relatively to one another and to the cooling surface, one 20 of the said members serving to apply the substance while the other one, being held at a certain distance from the cooling surface, serves to determine the thickness of the coating and to smooth this coating on the cooling 25 surface. One or both of said two members may, if desired, be heated by suitable means.

The cooling surface may be shaped as a cylinder, a truncated cone, a circular ring or 30 a plane table, and it may either be movable relatively to the stationary coating and smoothing members, or it may be at rest, while these are moving.

A manner of execution with rotary cylindrical cooling surface is represented on the drawing.

Figure 1 showing the apparatus, viewed in the direction of the axis of the cooling surface, partly in section, while Fig. 2 40 shows the apparatus in plan also partly in section.

The cooling surface K is shaped as a hollow cylinder, rotating about a hollow shaft through which the cooling medium, for instance a freezing mixture, is introduced into and discharged from the cavity of the cylinder. The member serving to spread the molten substance consists of a hollow body or sprinkler T, having on the side facing 45 the cooling surface a series of openings a, arranged sloping in relation to a spreading surface S provided below. The tubular wall of the sprinkler is considerably thicker where the openings a are located, so that

the latter form narrow channels, and the 55 size and shape of the openings may be varied, according to what is most suitable for the substances to be treated in the apparatus. By having the openings a slanting toward the spreading surface S, the molten 60 material, pressed out as small jets from the openings a, is caused to hit the spreading surface in such a manner that it is splashed up against the cooling surface as a thin 65 coating and adheres thereto. The spreading surface may be in fixed connection with the supply tube T, or it may be separated therefrom so that it may be adjusted at different angles or may be removed entirely, all according to what best suits the molten 70 substance in question.

The regulator R, serving to determine the thickness of the coating and to smooth it on the cooling surface, is placed above the spreading surface S and is carried by two 75 arms A which may be turned along the cooling surface and may be maintained at any desired level, for instance by means of arms O, as shown on the drawing.

The clearance between the cooling surface 80 and the curved side of the regulator R, facing the cooling surface, determine the thickness of the coating, and a downwardly directed sharp edge f on the regulator R serves to remove any surplus of substance deposited on the cooling surface. The regulator R may suitably be arranged as a hollow body, as it may then be kept heated by the introduction into its cavity of a heat transmitting medium, whereby any surplus 85 of substance removed from the cooling surface by the said member will melt and drip down on the spreading surface from where it will again be deposited at some other point of the cooling surface. 95

In order to insure the substance removed being actually conveyed down to the spreading surface the regulator R may suitably be fitted with a downwardly directed flange g, as shown on the drawing. The regulator 100 R may be made adjustable in many manners relatively to the spreading surface S and the cooling surface, so that not only its distance above the spreading surface may be varied by adjustment of the arm O, but also the 105 distance of the regulator R from the cooling surface, and the angle between the tangent of the cooling surface and the said

member's edge, facing the cooling surface, may be varied as desired, depending on what is suitable for the substance to be treated. Besides regulating the thickness of 5 the coating deposited on the cooling surface, the curved side of the regulator R, facing the cooling surface also serves to smooth the surface of the coating, for instance if the coating is uneven, on account of the substance, splashed up from the spreading surface S, being deposited thereon as small drops, it will be smoothed on the cooling surface by passing the heated regulator.

10 The layer deposited and cooled on the cooling surface is successively removed therefrom in known manner by means of 15 a knife k, located at such a point that the layer may remain for a suitable time on the cooling surface.

15 20 If it is found desirable to keep the sprinkler T in a heated condition similar means as mentioned in connection with regulator R may be used for this purpose.

Having now particularly described and 25 ascertained the nature of my said invention

and in what manner the same is to be performed, I declare that what I claim is:—

In an apparatus for cooling warm fluid matter such as molten substances or heated fatty emulsions, the combination with a 30 cooling surface of a hollow sprinkler adapted to be adjusted relatively to same and having at its side, facing the cooling surface, fine discharge apertures directed toward the cooling surface and serving to spread the 35 substance onto the same, and a hollow regulator adapted to be adjusted circumferentially as well as radially to said sprinkler and said cooling surface and to be heated by means of a heat transmitting fluid being 40 passed through its cavity and serving to remove any surplus of the substance deposited.

The foregoing specification signed at Copenhagen, this 21st day of January, 1913. 45

CHRISTEN CHRISTENSEN.

In presence of—

OVI GERSING,
JULIUS LEHMANN.
